(57) **CLAIM**

The ornamental design for a plumbing fixture, as shown and described.

DESCRIPTION

FIG. 1 is a left, top, front perspective view of a plumbing fixture embodying our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.

The dash-dash broken lines in the figures are for the purpose of illustrating unclaimed surfaces or environment of the design. The dot-dash-dot broken lines define unclaimed boundaries of the design. The broken lines are thus not part of the claim.

In a preferred embodiment, the nature of this product is as a plumbing fixture in the form of a tank and/or lid component for a water closet.
